UNITED STATES PATENT OFFICE.

GUST LAMPESSIS, OF MILWAUKEE, WISCONSIN.

CIGAR AND CIGARETTE HOLDER.

1,398,559.

Specification of Letters Patent. Patented Nov. 29, 1921.

Application filed February 1, 1921. Serial No. 441,542.

To all whom it may concern:

Be it known that I, GUST LAMPESSIS, a subject of Greece, and resident of Milwaukee, in the county of Milwaukee and State 5 of Wisconsin, have invented certain new and useful Improvements in Cigar and Cigarette Holders; and I do hereby declare that the following is a full, clear, and exact description thereof.

10 This invention relates to cigar and cigarette holders, and has primarily for its object to provide a holder adapted to form a container or inclosure for the cigar or cigarette whereby the same may be placed 15 in the pocket in a lighted condition without danger of fire, at the same time preventing any escape of smoke.

20 A further object of the invention is to provide a holder of this character with means for regulating the draft therethrough, thereby preventing the cigar or cigarette from too rapid or uneven burning when the same is being smoked while driving or exposed to high winds.

25 With these and other objects in view which will be apparent as the description proceeds, my invention consists in what is hereinafter more particularly described and pointed out in the specification and claims.

30 In the accompanying drawings:

Figure 1 shows a longitudinal view through the cigar holder embodying the features of my invention.

Fig. 2 is a transverse sectional view taken 35 upon the line 2—2 of Fig. 1.

Fig. 3 is a view similar to Fig. 2.

Fig. 4 is an elevational plan view of the holder.

40 Fig. 5 is a longitudinal sectional view through a modified form of the invention, particularly adapted for use in connection with cigarettes.

Fig. 6 is an enlarged transverse sectional view taken upon the line 6—6 of Fig. 5, and

45 Fig. 7 is a view similar to that shown in Fig. 6, and illustrates the method of opening the holder to remove the ashes.

Referring now more particularly to the accompanying drawings, the numeral 1 50 designates a housing having its top part cut away intermediate its ends to form an opening 2. Disposed within the housing is a sleeve or lining 3 with a cutout portion similar to that provided in the housing and in register therewith. Disposed between the sleeve and housing is a cover 4, adapted to be

rotated to form a closure for the opening 2 of the housing. When the cover is not in use it is rotated downward between the sleeve 3 and housing as shown in Fig. 3. 60

One end of the housing 1 is adapted to receive the reduced portion of a mouthpiece 5, which reduced portion is of a sufficiently tight fit to cause the sleeve 3 to be wedged between it and the housing, thereby preventing 65 it from becoming displaced with reference to the opening 2 of the housing. The opposite end of the housing 1 similarly receives the reduced neck of a spherical end closure 6 provided with a plurality of openings 6' to admit air within the housing when so desired. Disposed over the end closure 70 and threaded upon the end of the housing 1 is a shell 7, provided with holes adapted to register with the opening 6' of the end 75 closure to form a closure therefor when so desired.

A screen or perforated plate 8 is pivoted to one side of the housing adjacent the opening 2 and forms a cover for said opening 80 to prevent anything from coming in contact with the lighted cigar or cigarette when the cover 4 is open.

In operation the mouthpiece 5 is withdrawn from the housing and a cigar placed 85 within the tapered recess. The cigar is then inserted into the housing and passed through the loops 9 formed at the opposite end of a shank 10 constituting a guard to prevent the cigar from resting upon or coming in contact with the sleeve 3.

The screen 8 is then swung open to permit lighting the cigar, and if so desired, the cover 4 can then be revolved to close the opening 2 of the housing. Upon entering 95 a building or such place where it is not desired to smoke, the shell 7 can be rotated slightly upon the threaded end of the housing, causing the openings 6' of the end 6 to be closed, permitting the user to place the 100 holder in the pocket without danger of fire, and at the same time preventing the escape of smoke which might be obnoxious.

In Fig. 5 I have shown a modified form of my invention which is similar in principle 105 to that disclosed in Fig. 1. This form is particularly adapted to be used for cigarettes and comprises a housing 1' having disposed therein a lining 3'. In this form, however, instead of employing the rotated 110 cover 4 and the screen 8, I have substituted a perforated hinged plate 8' having its sides

bent back upon themselves at 11 to form guides for a shutter plate 12, having openings which can register with the openings in the cover 8' when so desired.

5 One end of the housing 1' is provided with a mouthpiece 5' similar to the mouthpiece 5, while the opposite end of the housing has fitted therein, an end closure 6" provided with suitable openings to permit air 10 to enter. The shutter plate 12 has secured thereto a nib 13 extending through a slot 13' in the cover plate 8' thereby permitting the shutter plate 12 to be shifted to form a closure for the perforations within the 15 plate 8'.

Positioned within the interior of the housing is a guard similar to that used in connection with that form shown in Fig. 1. It will be noted that in the structure shown in 20 Fig. 5 a flat end is procured which will permit the holder to be stood vertically upon its end.

While I have shown and described two forms in carrying out my invention, it will 25 be understood that various changes in details of construction are contemplated within the appended claims.

What I claim is:

1. A cigar or cigarette holder comprising 30 a housing provided with an opening, a cover adapted to close said opening, a detachable mouthpiece for one end of the housing and an end closure provided with openings for the opposite end of the housing.
- 35 2. A cigar or cigarette holder comprising a housing having an opening in its side, a slidible cover for said opening, a mouthpiece inserted in one end of the housing, an

end closure positioned in the opposite end of the housing and provided with openings, 40 and means for closing said openings.

3. A cigar or cigarette holder comprising a casing provided with an opening, a sleeve positioned within said casing and having an opening adapted to register with the opening in said housing, a cover positioned between said sleeve and housing, adapted to form a closure for the opening in said sleeve, a mouthpiece for one end of the housing, a closure for the opposite end of the housing, 50 said closure being provided with openings, and means for closing said openings.

4. A cigar or cigarette holder comprising a housing having an opening in its side, a lining for said housing, a rotatable cover 55 positioned between the housing and lining, a mouthpiece for one end of the housing, and a closure provided with openings for the opposite end of the housing, said mouthpiece and closure being adapted to wedge 60 and hold the lining in place.

5. A cigar or cigarette holder comprising a housing provided with an opening, a lining positioned within said housing and provided with an opening adapted to register 65 with the opening in said housing, means adapted to close the opening in the housing, a mouthpiece for one end of the housing, and means positioned within the opposite end of the housing to regulate the draft 70 therethrough.

In testimony that I claim the foregoing I have hereunto set my hand at Milwaukee, in the county of Milwaukee and State of Wisconsin.

GUST LAMPESIS.
